RESPIRATORY FILTERING DEVICE

Joseph B. Biederman, Cincinnati, Ohio

Application January 7, 1943, Serial No. 471,603

2 Claims. (Cl. 128—146)

1

This invention relates to improvements in a respiratory filtering device and particularly to improvements on applicant's copending application Serial Number 408,627 and to improvements in the replaceable filtering pad used therewith.

The principal object of this invention is the provision of a respiratory filtering device that is inexpensive to manufacture yet sturdy of construction and easy to operate.

Another object of this invention is the provision of a filtering device, as above set forth, with which an improved filter pad may be employed to provide a definite seal around the nose and mouth of the user.

Another object of this invention is the provision of a filtering device that will conform with the contour of the face of the user around the nose and mouth without uncomfortably clamping itself against the user's face.

A further and specific object is the provision of a replaceable filter pad for use with a respiratory filtering device that will not bunch and will lie flat between the device and the face of the user to form a perfect seal against air passing therearound to the nose and mouth of the wearer.

Other objects and advantages of the present invention should be readily apparent by reference to the following specification considered in conjunction with the accompanying drawing forming a part thereof and it is to be understood that any modifications may be made in the exact structural details there shown and described, within the scope of the appended claims, without departing from or exceeding the spirit of the invention.

In the drawing:

Fig. 1 is a front elevation of a respiratory filtering device embodying the improvements of this invention.

Fig. 2 is a vertical sectional view through the device taken on line 2—2 on Fig. 1.

Fig. 3 is a horizontal sectional view through the device taken on line 3—3 on Fig. 1.

Fig. 4 is a fragmentary elevational view of a portion of the device as seen from line 4—4 on Fig. 2.

Fig. 5 is an enlarged fragmentary sectional view through the clamp of the device taken on line 5—5 on Fig. 1.

Fig. 6 is a plan view of the filter pad as used in the filtering device of this invention.

Fig. 7 is an edge view of the filter pad illustrated in Fig. 6.

Throughout the several views of the drawing

2

similar reference characters are employed to denote the same or similar parts.

The respiratory filter of this invention comprises a body member 10 of a general U shape having in effect arms 11 and 12 connected together by a base portion 13. The outer edges of the arms 11 and 12 are substantially regular in outline while the inner or opposed edges of said arms are cut away as at 14 and 15 to outline the nose and mouth of the user. The said contoured edges of the arms are provided with an upturned flange 16 so that a rounded edge is presented to the face instead of a sharp edge of the sheet metal from which the body member 10 is stamped.

The upper ends of the arms 11 and 12 are connected by an elastic member 17 which as illustrated in the drawing is elastic fabric. In practice the elastic member 17 follows the contour of the wearer's nose with end of the arms lying at the base of the nose.

As seen in Fig. 3 the mask body 10 is transversely curved so as to conform to the curvature of the face of a user. In order to hold the mask 25 in position the arms 11 and 12 are respectively provided with a piercing resulting in an upturned hook 18 and 19 to which, respectively, is removably attached a coupling 20 and 21 having between them an elastic mask attaching band or strip 22 which encircles the back of a user's head.

Cooperating with the mask body 10 is a wire frame 23 having, in front elevation, the form illustrated in Fig. 1 which, as will be noted, has an outline substantially identical with the opening of 35 the U frame. The wire frame 23 comprises an arcuate transverse portion 24 from which depends sides 25 and 26 contoured similarly to the contours 14 and 15 of the arms 11 and 12. Integral with and extending from the wire frame sides 40 25 and 26 are arms 27 and 28 which project toward one another for a distance and then are rearwardly directed as at 29. The rear end of the arms 27 and 28 bend downwardly to provide legs 30 and 31 with their lower ends outwardly 45 projected to form trunnions 32 and 33, as will later be made clear.

The base 13 of the filter body member 10 substantially centrally thereof is offset to provide a channel 34 of a width substantially equal to the 50 distance between the wire frame legs 30 and 31. The sides 35 and 36 of the offset 34 are adapted to be engaged by the wire frame legs and the said sides are each provided with an aperture 37 through which projects the trunnions 32 and 33. By this construction the wire frame 23 is

adapted to be oscillated from the position illustrated in full lines in Fig. 2 to the position illustrated in dotted lines therein. With the frame in the dotted line position of Fig. 2 a filtering pad 38, of Figs. 6 and 7, may be placed on the underside of the filter body for subsequent positioning. The wire frame 23 is oscillated from its dotted line position to the solid line position of Fig. 4 thereby positioning the filter pad 38 outwardly of the nose and mouth of a wearer while having the marginal portion of the pad 38 between the filter body portion 10 and face.

In order to retain the wire frame 23 in its operative position use is made of a locking device illustrated most clearly in Fig. 4. The locking device comprises a locking member of substantially T shaped formation comprising a cross member 39 providing arms 40 and 41 with a tongue 42 depending from the cross member from between the arms 40 and 41. The ends of the arms 40 and 41 are upwardly bent or arched as at 43 to lie on the upper surfaces of the legs 30 and 31 when clamping the wire frame in position. In order to oscillate the clamping member it is connected by a rivet 44 to the base of the offset 34.

The filter pad 38, as noted above, engages with the undersurface of the filter body 10 and the face of a user and thereby acts as a seal against infiltration of air except by way of the open wire frame 23 and therearound through the filter pad. In order that a seal may be so provided and to prevent bunching of the pad upon actuation of the wire frame the pad 38 is cut as illustrated in Fig. 6. As there illustrated the pad is generally semi-circular in outline with a substantially straight lower edge 45 and which outline conforms with the general outline of the filter body except for being somewhat larger in area. Extending into the pad from its lower edge are a pair of cuts 46 and 47 providing between them a tongue 48. In practice the tongue 48 is drawn down between the wire frame legs 30 and 31 affording a means for holding the pad in position during the oscillation of the frame from the dotted to the solid line position of Fig. 2 and preventing a bunching or upward movement of the said pad by the wire frame legs which would occur if the pad were not provided with the tongue 48 and cuts 46 and 47 which provide passageways for the said legs. By this construction the seal at the lower end of the mask body, or across the base 13, is maintained instead of being broken as would be the case with a tongueless pad.

The filter pad 38 may be cut from any filtering material on the market, such as is illustrated, comprising a woven gauze like layer 49 and a fibrous or cotton layer 50. With this type of

filter the fibrous or cotton layer does the filtering and is of considerable thickness with the woven fabric layer 49 acting merely as a reinforcing backing for the filter.

For clearness in illustration the filter pad 38 is shown in certain of the views of the drawing in phantom lines.

From the foregoing it will be noted that there has been provided a respiratory filtering device comprising a single member of sheet material which may be either metal or plastic and of a general U shape to lie below and around the nose and mouth of a person. Associated with this single member is a simple wire frame capable of being positioned ahead of the single sheet member for holding a filtering pad in front of the respiratory organs. It will further be noted that there has been provided a filtering pad of a particular outline or contour and construction adapted for use with the filtering device of this invention and which will provide a definite seal around the respiratory organs.

What is claimed is:

1. In a device of the class described the combination of a body member having a central opening for the respiratory organs comprising a base member and arms at the ends of the base member, said base member having a channel like offset, a wire frame having depending legs journaled in the channel walls for movement between the body member arms to a position ahead of the respiratory organs and a filter pad located in front of the wire frame and behind the body member, and said filter pad having a tongue portion extending between the wire frame legs whereby the said filtering pad extends at least to the bounding edge of the body member, and means for locking the wire frame in its forward position, comprising a T shaped member pivotally mounted in the offset channel having arms adapted to overlie the wire frame legs and a tongue projecting below the body member.

2. In a device of the class described the combination of a U shaped body member adapted to have its arms disposed on each side of the respiratory organs and its base portion therebelow, an elastic fabric connection between the free ends of the arms for overlying the nose, a wire frame oscillatably mounted on the base of the U shape frame for oscillatory movement between the arms to a position ahead of the U frame, means for locking the wire frame in its forward position, and a filter pad disposed ahead of the wire frame and behind the U shaped body member and connecting elastic fabric and having a tongue overlying the wire frame locking mechanism.
